AUTOMOBILE LOCK

Edward L. Kulick, Milwaukee, Wis., assignor of
one-half to Clara M. Farrell, Chicago, Ill

Application April 7, 1928, Serial No. 268,095

22 Claims. (Cl. 200—19)

My invention relates to automobile locks and more particularly to an improved type of ignition lock.

Specifically, the invention provides mechanism for permanently grounding the ignition circuit in the event an unauthorized attempt is made to wire around the lock switch on the dash board, by cutting the cable and connecting the ignition wire directly to a source of current supply, such as the battery.

In order to apprise those skilled in the art how to construct and practice my invention, I shall now describe several preferred embodiments thereof taken in connection with the accompanying drawings forming a part hereof.

In the drawings:

Figure 1 is a top plan view of a distributor illustrating the manner in which the circuit grounding mechanism is effectively locked to the distributor;

Fig. 2 is a side elevational view of the device illustrated in Fig. 1, being partly broken away to show the switch grounding mechanism and a portion of the distributor in section;

Fig. 2a illustrates the switch locking mechanism located on the dash board of the automobile.

Fig. 3 is a wiring diagram of one form of circuit;

Fig. 4 is a horizontal sectional view taken on line 4—4 of Fig. 2;

Fig. 4a is a vertical sectional view of one form of element used in the circuit grounding mechanism for establishing a ground connection.

Fig. 5 is a perspective view of the distributor with the cap and guard plate omitted and the switch grounding mechanism disassembled therefrom;

Fig. 6 is a detail view illustrating the manner in which the housing carrying the switch grounding mechanism is fitted in interlocking engagement with a plate secured to one side of the distributor;

Fig. 7 is a bottom plan view of the device shown in Fig. 6;

Fig. 8 is a transverse vertical sectional view taken along line 8—8 of the housing of switch grounding mechanism shown in Fig. 5;

Fig. 9 is a perspective detail view of a guard plate inserted within the housing;

Fig. 10 is a view similar to Fig. 2 but illustrating another form of my invention;

Fig. 11 is a transverse vertical section taken along line 11—11 of Fig. 10;

Fig. 12 is a vertical sectional view taken along line 12—12 of Fig. 11;

Fig. 13 is a transverse vertical sectional view taken along line 13—13 of Fig. 10;

Fig. 14 is a detail view in perspective of a fusible device; and

Fig. 15 is a vertical sectional view of another form of my invention.

My invention comprises essentially a lock switch 10 operated by a key 11 and an ignition circuit including a distributor or ignition wire 12, a battery wire 13, a coil 14 connected thereto between when lock switch 10 is closed and a fusible element 15, including a grounded wire 16 and a permanently open grounded circuit divided into a plurality of leads 17, 18 and 19. Wire 12 is connected to a distributor 20. The ignition system is completed through a ground wire 22 and a ground connection 23 at one end of a battery 24. Wires 12 and 13 are connected to switch 10 at terminals 25 and 26, respectively. A third terminal 27, together with terminal 25, permits the insertion of coil box 14 in the circuit. A fourth terminal 28 provides a connection for one end of a permanently grounded wire 29 having a resistance 30 therein and grounded at the opposite end at 16, the purpose of which will be presently described.

These terminals are suitably mounted at one end of locking mechanism 10. This locking mechanism may be of the ordinary type having a lock cylinder operated by key 11. Terminals 25, 26, 27 and 28 are adapted to be engaged by movable contact 30, which is carried at one end of the lock cylinder and rotated by key 11.

It is the purpose of the disclosure herein to adopt any well known substantial and rugged form of locking mechanism, which is simple and not easily picked or broken.

When the ignition circuit is closed, contact 30 is in the position illustrated in full lines in Fig. 3. Current will flow from battery 24 through wire 13, terminal 26, movable switch contact 30, and from terminal 27 through coil box 14 to terminal 25, through wire 12 to distributor 20.

It will be observed that an open lead 31, connected to terminal 26, lies parallel to wire 12 and false wires 17, 18 and 19. When wires 12, 17, 18 and 19 and wire 31 are embodied in a cable, cutting the cable or removing the insulation from the wires will invariably cause wire 31 to contact with any or all of the wires 17, 18 and 19. Wire 31 is a live wire at all times, irrespective of the position of movable switch contact 30, because such wire 31 is directly connected to battery wire 13 at terminal 26, as illustrated in Fig. 3.

Contact of wire 31 with either or all of false

wires 17, 18 or 19 completes the circuit of fusible element 15 through the grounding connection 16 and 23. A flow of current through fusible element 15 functions to establish a permanent ground connection for wire 12, by releasing a spring finger 32. Finger 32 is pivoted and is yieldably held from normal engagement with a pin 33 in the circuit of wire 12. The pivoted end of finger 32 is preferably connected to ground connection 16. Finger 32 is, therefore, constantly grounded and serves the purpose of providing or establishing a ground connection for wire 12 when current flows through fusible element 15.

It will be observed, therefore, that operation of fusible element 15 permits spring finger 32 to snap into engagement with pin 33 to cause the ignition circuit to be grounded at 16. The result of this action is that it would be further impossible to shunt the circuit to the battery 24 to nullify the locking effect of mechanism 10 herein provided. Any number of false wires may be provided for the open grounded circuit in the cable enclosing the same and connecting to the locking mechanism 10, but the effect is to allow wire 31 accidentally to contact with either of the false wires thus provided. Assume, however, that a portion of the outside covering of the cable has been removed and the wires are exposed for a considerable distance toward the lock mechanism 10. Access to the connections at this mechanism 10 will be prevented by an armour tube 35 securely attached to lock mechanism to protect the cable end. Armour tube 35 extends along cable 36' a sufficient distance to act as a protective means, which prevents unraveling of the insulation or covering of the cable to gain access to the switch terminals. Should the wires be exposed, however, as just explained, it will be impossible to determine which wire is the distributor wire leading to the distributor. Experiments have indicated that it is very unlikely for a person accidentally to choose distributor wire 12 before choosing either of the wires 17, 18 or 19. Once either of the wires 17, 18 or 19 is connected to the battery circuit, or source of current supply, fusible element 15 operates to ground the ignition circuit at 16. First testing the wires thus chosen to determine whether a spark is given when the engine is turned over will be of no avail, because this also causes fusible element 15 to ground the circuit, if any of wires 17, 18 or 19 is chosen.

In order to prevent an unauthorized person or thief from wiring around or short-circuiting distributor wire 12 by removing distributor cap 36 and connecting a jumper between terminal 37, shown in Fig. 2, and terminal 38 of coil box 14, and a jumper between the battery 24 and terminal 39, so as to circumvent the effective grounding action of the ignition circuit, as just described, when locking mechanism 10 is in open position with movable conductor 30 in the dotted line position shown in Fig. 3, a permanently grounded wire 29 is provided. More particularly, wire 29 furnishes a ground connection for distributor wire 12 when the circuit is opened by lock mechanism 10.

Except for cutting cable 36', which will establish a ground connection by the fusing of element 15, effective access to wire 12 is practically impossible due to armour tube 35 at switch locking mechanism 10 and a similar armour tube 40 at the distributor end. Destruction of wire 12 between terminals 25 and 27 of lock mechanism 10 and coil box 14 and the placing of short-circuiting jumpers between the battery 24 and the coil box 14 and between the coil box and

the distributor 20 at the terminal 27 thereof, will not nullify the effect of the permanently grounded wire 29 to prevent supplying current to the distributor, because the current will flow back from distributor 20 through the wire 12 across movable switch contact 30 to grounded wire 29. This prevents the current from flowing through the distributor to secure proper operation of the ignition system. It will be noted, therefore, that when lock mechanism 10 is in open position with the movable contact 30 in dotted line position, as shown in Fig. 3, the ignition system is effectively grounded by the wire 12 connected to grounded wire 29 whereby to prevent any attempted tampering to avoid the grounding action at the fusible element 15 when the cable is cut.

Any suitable mechanism may be employed for carrying out my invention. I prefer, however, as illustrated in the drawings, to embody fusible element 15 in a housing 45, which is adapted to be fastened against a substantially flat plate 46 on distributor 20. As illustrated in Figs. 1 and 5, plate 46 has its vertical edges 47 slightly bent or forwardly curved to act as interlocking edges 100 with the edges 48 of housing 45.

One of the features of my invention is interlocking to engage housing 45 with plate 46 to prevent removal of this housing after it is mounted in position. This feature is obtained by providing a spring finger 49 securely fixed by riveting at 51 to an insulation plate 50 carried within housing 45. The upper portion of spring finger 49 is bent outwardly so that, as it slides over distributor terminal 52, it will be compressed, 110 but will again spring outwardly to engage against the under edge 53 of terminal 52 formed by cutting the lower portion away. The upper half of distributor terminal 52 has sufficient body thereto to overcome any force employed to shear 115 it if an attempt is made to lift housing 45 upwardly by a blow or other destructive means.

Plate 46 closes off the open rear face of housing 45, when the latter is mounted in position thereon, by edges 48 of housing 45 lying over the inwardly bent edges 47 of plate 46. Housing 45 is preferably made of pressed steel and formed with its bottom slightly open, as indicated at 54, to receive the horizontally extending flat piece 55 bent outwardly from plate 46. The purpose 125 of bending the bottom piece 55 outwardly from plate 46 is to allow for the provision of an opening 56 accommodating condenser wire 57 leading from distributor terminal 52 to condenser 58. After housing 45 is mounted in position, further 130 downward sliding movement is prevented by the upper edge 59 of plate 46 engaging within the underside of the top face 60 of housing 45. Edge 59 has an upwardly extending lug 61 thereon which lies in a correspondingly shaped slot 62 135 in the top face 60 of housing 45, so as to assist in securing a rigid interlocking engagement between housing 45 and plate 46. The intermediate portion of plate 46 may be provided with depressions 61 therein to furnish a substantial bearing for the plate against the outer surface of the distributor.

It will be understood that it is a novel feature of this invention to embody the fusible element 15 in a housing secured directly to distributor 20. 145

It will also be observed that I have shown several different forms of fusible elements and in so far as the invention is concerned, any particular form may be adopted.

In the form shown in Figs. 1 to 3, inclusive, 150

fusible element 15 comprises a cartridge 65, having end conductors 66 and 67 provided with projecting pins 68 and 69. The wall 70 of the cartridge is preferably of glass and confines therein an explosive substance 71, such as powder, adapted to ignite and break glass wall 70 when a central fusible wire 72 melts upon a flow of current therethrough.

Cartridge 65 is normally seated and held between spring finger 32 and a forwardly extending ear 74 carried by a conductor fastening 75, the pins 68 and 69 entering openings in the finger and ear so as to secure perfect contact and prevent side displacement of the cartridge.

Both the spring finger 32 and the conductor fastening 75 are mounted on a plate of insulation 76, which plate is inserted in housing 45, as is clearly illustrated in Fig. 2. The false wires 17, 18 and 19 in cable 36 enter housing 45 and connect by means of a screw 77 to a forwardly extending portion 76' of conductor fastening 75. Finger 32 is pivotally mounted on a pin 78 carried by insulation plate 76, as illustrated in Figs. 2 and 8. A coil spring 81 encircles pin 78 and has one end engaging against floor 79 of housing 45 and the other end against the underside of finger 32 as indicated at 80. Coil spring 81, therefore, tends to urge finger 32 upwardly to hold cartridge 65 between it and the projection 74 on conductor fastening 75. The lower leg of spring 81, engaging against housing 45, provides a permanently grounded connection for finger 32. Ignition wire 12 enters housing 45, as illustrated in Fig. 8, to connect with a terminal 82. Terminal 82 is provided with the forwardly projecting conductor pin 33 which is adapted to pass through an opening 84 in plate 50, as illustrated in Fig. 5, whereby to contact with the spring connector 49 for completing the circuit through the primary interrupter terminal 52 to distributor 50. It is desirable to place a drop of solder 85 over the end of pin 33 to secure it to connector 49, as illustrated in Fig. 4. It will also be observed in Fig. 4 that pin 33 is reduced at 84 to provide a shoulder which, together with the forward end of pin 78, provides proper abutments against which plate 50 is held.

Grounded wire 29 is brought into housing 45 from cable 36' and is connected at 87 to a terminal between which and another terminal 88 a resistance coil 89 is interposed. A short connection 90 is then provided between terminal 88 and the floor 79 of housing 45 for the purpose of establishing a ground for wire 29.

From the foregoing description, it will be apparent that a flow of current through fusible wire 72 will ignite the powder 71 and cause the cartridge 65 to explode. The glass wall 70 will be shattered to permit the action of spring 81 to raise finger 32 into contact with pin 33 connected to wire 12. This latter wire 12 is thereby grounded so as permanently to ground the ignition circuit. The purpose of cartridge 65 is positively to hold spring finger 32 out of contact with pin 33 and to provide an immediate release thereof when current flows through its central fusible wire 72.

It will be understood, of course, by those skilled in the art that it is practically impossible to devise locking mechanism which is totally devoid of access or of being tampered with by an unauthorized person or a thief. The closest approach to absolute security is the construction of a design requiring maximum time for its destruction, that is to say, a construction so designed as to deter or hamper quick action on the part of the

thief in rendering the locking structure ineffective. To this end I have provided an armour plate 92, which is circular, and which is apertured at 93 to fit into the distributor and over its central shaft. Plate 92 is furnished with spaced downwardly projecting lugs 94 having threaded openings 95 for receiving the usual screws 96 which fasten a plate 97 carrying the well known contactor arm 98. Plate 97 is usually furnished with upstanding lugs 99 having threaded openings 100 for receiving these screws 96.

The purpose of plate 92 is temporarily to frustrate any attempt to disconnect conductor 103 from inner end 37 of distributor terminal 52 and attach a jumper which leads to the coil or other proper connection so as to avoid this grounded distributor terminal. It will be noted in Fig. 4 that plate 92 lies over inner end 37 of terminal 52 to the extent that it is impossible to reach under the plate to disconnect conductor 103 without first removing the plate. The advantage of the use of plate 92 resides in the fact that the thief must first back off screws 96, in order to lift plate 92 out of the distributor. Those skilled in the art appreciate that some time is required to perform this work, and consequently, the security of the lock is thereby increased to this extent. On the other hand, very few thieves will undertake the removal of plate 92 in view of the fact that the length of time required to remove the plate is apt to attract attention and cause suspicion of those persons who may pass by at the time.

Another form of my invention is shown in Figs. 10 to 14, inclusive. This construction is very simple and practical, and is inexpensive to manufacture on quantity production. The mode of attaching housing 45 to distributor 20 is substantially the same. I prefer in this embodiment to employ a different form of fusible element 15. Insulation block 76 is cut away at 110, as noted in Fig. 13, to receive a cartridge 105 comprising end conductors 111 and 112 spaced by an insulated body 113, and having an interconnecting fusible wire 114 disposed therebetween along the outside of the body 113. End conductor 112 is seated in electrical contact with a conductor plate 115, to which is secured at 116 the false wires 17, 18 and 19. Upper end conductor 111 is similarly seated in electrical contact with a conductor plate 117 having a forwardly projecting lip 118 adapted to rest and to be grounded against the underside of the upper wall of housing 45, this being clearly seen in Fig. 12. Attached, as by riveting at 119, is a spring finger 120 held under tension at its free end by a ribbon 121 passing around the insulated body of cartridge 105 so as to engage against a portion of fusible wire 114, this ribbon being tied at 122 at the front of the finger. Ribbon 121 may be of any suitable material capable of releasing finger 120 upon a flow of current through wire 114, such release being accomplished either by the ribbon burning, or otherwise being destroyed by the hot wire 114. This wire will heat upon a flow of current therethrough to the extent of burning or destroying the ribbon 121, so as to separate it at the line of engagement therewith whereby to release the restrained spring finger 120. In this embodiment, insulation block 50 is provided with a conductor rivet 123 passing therethrough to furnish a face 124 immediately adjacent the tip 125 of spring finger 120. Conductor rivet is attached in electrical relation to member 49 which completes the normal igni-

tion circuit through cable 36 to the distributor at the distributor terminal 52.

Ignition wire 12 extends into housing 45 and attaches therein to a conductor plate 126 at the point 127. Conductor plate 126 has a forwardly projecting lip 128, which passes through insulation block 50, as noted at 129 in Fig. 10, so that its forward end may be bent upwardly, as indicated at 130, to contact with the lower edge of spring finger 49. It will be noted, therefore, that upon the burning or destruction of the ribbon and the release of spring finger 120, which is grounded at 118 to housing 45, the forward tip 125 of finger 120 contacts with the inner face 124 of conductor rivet 123, thereby to ground the normal ignition circuit. Burning of ribbon 121 is the result of the current flowing through wire 114, as above stated, this being produced by cutting of the cable so as to bring any or all of false wires 17, 18 or 19 into contact with the open live wire 31, which is connected to battery 24 or other source of current supply.

Grounded wire 29 enters housing 45 and passes through insulation plate 76 on the reverse side of insulation plate 76, connecting at 130 to conductor plate 115 by means of the conductor strip 131 leading to point 116, to which false wires 17, 18 and 19 are connected at the front side. This grounded wire 29 is indirectly connected to upper conductor plate 117 by means of a resistance coil 133, which passes through a passage 134 angularly cut in insulation plate 76 (see Fig. 13) and through another passage 135 horizontally cut to permit resistance coil 133 to contact with conductor 118 at the point 136, as shown at one side of plate 76 in Fig. 12. The purpose of this arrangement is to permit wire 29 to have the same function as any one of the false wires 17, 18 and 19 in the event the cable is cut and live wire 31 brought into contact with wire 29. The current will flow directly to conductor plate 115 through fusible wire 114, the conductor plate 117 and ground at the extension 118, thereby causing ribbon 121 to burn and release finger 120 so as to ground the ignition wire 112 through finger 120.

Another form of the invention is shown in Fig. 15. In this embodiment the releasable spring finger 140 is normally carried on the rear face of insulation block 50 and is connected in circuit at the point 141, to which ignition wire 12 is attached. Spring finger 49 is attached to the connection 141 on the front side of ignition block 50 so as to complete the circuit through the distributor at terminal 57. A grounded plate 142 is mounted within housing 45 and spaced a predetermined distance to the rear of insulation plate 50. At the upper end of insulation plate 50, I provide a conductor connection 143 to which the false wires 17, 18 and 19 are connected. Spring finger 140 is normally held under tension by a fusible wire 145 connecting between conductor plate 143 and the tip of this finger. Grounded wire 29 connects to grounded plate 142 at the point 143. In the event open live wire 31 contacts with either of false wires 17, 18 or 19, the current will flow through fusible wire 145 and cause the same to fuse and release spring finger 140 whereby to allow the latter to flip backwardly and remain in contact with grounded plate 142. The ignition circuit is thereafter permanently grounded and without gaining access to the interior of housing 45, it is impossible to remove this grounded connection.

It is not necessary to dispose the fusible element 15 in either of the embodiments above described adjacent to the distributor, but it is preferable to ground the circuit as close to the distributor so as to eliminate any possible shorting around for the purpose of avoiding the ground. All three forms of fusible element 15 have been found to be practical and simple, and effectively establish a ground in the event current flows therethrough. The mechanism employed will not permit the cable to be cut and consequently the thief will find himself in a position requiring more time to avoid the locking mechanism than is feasible, if he is not to create attention or cause suspicion. Relying on the heat effects of the current flow for establishing a ground assures quick and positive action at all times and eliminates possibility of parts failing such as might occur if other means are employed.

While in the foregoing I have described what I now consider to be several preferred embodiments of my invention, it is to be understood that various changes in the construction, combination and arrangement of parts may be resorted to within the scope of the appended claims.

I claim:

1. In an ignition system, including a distributor, the combination of a lock for the ignition wire, a cable between the said lock and said distributor, said cable including the ignition wire, a plurality of false wires and an open live wire, and means operable by the heat effects of the current flow to establish a ground connection in the ignition wire upon contact of either of said false wires with said open live wire.

2. In an ignition system, the combination of a

switch for controlling the ignition wire, means for establishing a grounded connection in said ignition wire, and a plurality of false wires adapted

115 to cause actuation of the grounding means by

the heat effects of the current flow therethrough

when either of said false wires are connected to a

source of current supply.

3. In an ignition system, including a distributor, the combination of a switch for the ignition wire, a cable between said switch and said distributor, said cable including the ignition wire, a false wire and an open live wire, and means disposed at said distributor operable by the heat effects of the current flow to establish a ground upon contact of said false wire with said open live wire.

4. In an ignition system including a distributor, the combination with a switch for the

130 ignition circuit, a cable between said switch and said distributor, said cable including an ignition wire, a false wire and an open live wire, and fusible means operable to establish a ground in the

ignition circuit upon contact of said false wire with said open live wire.

5. In an ignition system, the combination of a switch for controlling the ignition circuit, electrical means operable by the heat effects of the current flow for establishing a ground connection in said ignition circuit, and false wiring adapted to cause actuation of said electrical means when said false wiring is connected to a source of current supply.

6. Theft preventing apparatus for automobiles comprising, in combination, an igniton timer, a conduit extending therefrom with current conducting means therein, lock mechanism at the other end of said conduit for locking said circuit open, and means operable by the heat effects of

- the flow of current through said current conducting means for establishing a ground for said timer.
7. Theft preventing apparatus for automobiles comprising, in combination, an ignition circuit including a timer and a conduit extending therefrom with current conducting means therein, means at the other end of said conduit for opening and closing said circuit in its normal operation, and means for rendering said circuit inoperative, including a member operable by the heat effects of the flow of current through said circuit and movable when operable to ground said circuit.
15. Theft preventing apparatus for automobiles comprising, in combination, an ignition circuit including current conducting means and a switch connected therewith for normally opening and closing said circuit, and means for rendering said circuit inoperative, said means being operable by the heat effects of the flow of current through said circuit upon an attempted unauthorized access to said current conducting means.
20. In an igniton system, the combination with an ignition wire, of means for producing a current flow upon mutilation of said ignition wire, and means operable by the heat effects of the current flow to establish a ground connection in said ignition wire.
25. 10. In an ignition system, the combination with an igniton wire, of a grounded false wiring and an open live wire for producing a current flow by an attempted destruction of said igniton wire, and means connected to said false wiring operable by the heat effects of the current flow and having provisions for contacting with said ignition wire to ground the same upon operation of said means.
30. 11. In an ignition system, the combination with an ignition circuit, of means for establishing a ground connection in the ignition circuit comprising an open grounded circuit having a fusible element therein, a releasable member connected in said grounded circuit, means contacting with said fusible element and surrounding said releasable member for normally holding said member out of contact with said ignition circuit, said means being influenced by the heat effects of the current flow through said fusible element to release said member.
35. 12. In an ignition system, the combination with an ignition circuit, of mechanism for establishing a ground connection including a heat element, a grounded member, and means contacting with said heat element and normally fastening said member to prevent contact with said ignition circuit, and means for providing a current flow through said heat element whereby to destroy said first means and release said member.
40. 13. In an ignition system, the combination with an ignition circuit, of mechanism for establishing a ground connection including a heat element and means for providing a current flow through said heat element, a releasable member normally held out of contact with said ignition circuit, and a combustible ribbon in contact with said heat element and holding said releasable member out of contact with said ignition circuit, said combustible ribbon adapted to burn and release said member upon a current flow through said heat element.
45. 14. In an ignition system including a distributor-timer, the combination of a switch for the ignition wire, a cable between said switch and said distributor for said ignition wire, means for grounding said ignition wire upon mutilation of said cable, and means for grounding said ignition wire by the movement of said switch to open position.
50. 15. A lock for controlling the circuit leading to a distributor-timer of an ignition system including a switch, a housing adapted to be mounted on said distributor, means disposed in said housing for rendering said circuit inoperative, and means operable by the mounting of said housing on said distributor for interlockingly engaging said housing to said distributor.
55. 16. A lock for controlling the circuit leading to a distributor-timer of an ignition system including a switch, a housing adapted to be mounted on said distributor, means in said housing for rendering said circuit inoperative, and means operable by the positioning of said housing on said distributor for automatically interlocking said housing to said distributor.
60. 17. In an ignition system, the combination of a distributor-timer having the usual body containing a breaker arm spring and the usual cap attached directly to said body, a protective guard element in said body and protecting said breaker arm spring against unauthorized displacement, and mechanically removable means for mounting said element in said body.
65. 18. In an ignition system, the combination of a distributor-timer having the usual body and the usual cap attached to said body, a protective guard element in said body for protecting an operative part of said distributor-timer, and means for mounting said element, said mounting means holding said guard element within said body in its protective relation with said operative part of said distributor-timer.
70. 19. Theft preventing apparatus for automobiles comprising, in combination, a timer of an ignition circuit having a breaker arm carrying a movable contact engageable with a relatively stationary contact for the normal control of said circuit, a terminal to which said breaker arm is connected, a housing adjacent to said timer adapted to contain therein means for rendering the operation of said timer contacts ineffective to control said ignition circuit, and means including said terminal for attaching said housing to said timer.
75. 20. Theft preventing apparatus for automobiles comprising, in combination, a timer of an ignition circuit having contacts within the body therefor for the normal control of the circuit, a terminal for one of said contacts carried by the timer body, a housing adapted to contain therein means for rendering the operation of the timer contacts ineffective to control the ignition circuit, and means carried by the housing cooperating with the terminal for locking the housing to the timer body.
80. 21. Theft preventing apparatus for automobiles comprising, in combination, a timer of an ignition circuit having contacts within the body therefor for the normal control of the circuit, a terminal in the circuit extending through the timer body, a lock-controlled device for controlling the circuit located at a point remote from the timer current conducting means between the timer and the lock-controlled device, a connection between the current conducting means and the terminal, a housing adapted to be attached to the timer body to enclose said connection, and means automatically locking the housing against removal when the housing is moved into its position upon the timer body.

22. Theft preventing apparatus for automobiles comprising, in combination, a timer of an ignition circuit having contacts within the body thereof for the normal control of the circuit, a terminal connected in circuit with one of the contacts and carried by the timer body in a manner to expose one face of the terminal exteriorly of the timer body, means for normally controlling the on and off relation of the circuit located 10 at a point remote from the timer, current con-

ducting means between the timer and the normal circuit controlling means, a connection between the terminal and the current conducting means, a housing for enclosing said connection, and means for attaching the housing including a plate fixed against the timer body by the terminal, the plate and terminal cooperating with the housing and connection to lock the housing against removal. 80
